UNITED STATES PATENT OFFICE.

FREDERICK K. VREELAND, OF MONTCLAIR, NEW JERSEY, ASSIGNEE TO VREELAND APPARATUS COMPANY, INC., OF NEW YORK, N. Y., A CORPORATION OF NEW YORK.

METHOD OF TRANSMITTING AND RECEIVING HIGH-FREQUENCY SIGNAL IMPULSES.

1,245,166.

Specification of Letters Patent.

Patented Nov. 6, 1917.

Application filed October 18, 1907, Serial No. 397,961. Renewed September 18, 1917. Serial No. 192,033.

To all whom it may concern:

Be it known that I, FREDERICK K. VREELAND, a citizen of the United States, residing in Montclair, county of Essex, State of

5 New Jersey, have invented a certain new and useful Improvement in Methods of Transmitting and Receiving High-Frequency Signal Impulses, of which the following is a specification.

10 My invention relates to the method of transmitting and receiving sustained high frequency signal impulses involving the "beat" principle or principle of differential frequencies set forth in my application, Serial No. 350,476, filed January 2, 1907. By the method which constitutes the present improvement the signals are made imperceptible by any other form of receiver thus far produced, the flexibility of the receiving apparatus is increased and the transmitting apparatus is simplified.

15 In carrying out my present method the transmitter is arranged to send out a continuous uninterrupted train of waves and the signals consist preferably in minute variations in the frequency of these waves, without (or with if desired) changes in intensity. These frequency changes are preferably too small to be effectively observed 20 by electrical resonance, although the invention is applicable where the changes are comparatively large. At the receiving end the local oscillator generates currents of a constant frequency slightly different from 25 that of the transmitter, which produce beats in the receiver by interference with the oscillations received from the transmitter. The difference in frequency of the two oscillators is preferably so chosen as to produce a 30 beat tone of convenient musical pitch. The minute additional differences which constitute signal impulses will produce variations in this pitch which constitute the signals, *i. e.* tones of a different pitch breaking 35 in on the constant ground tone which represents the no-signal state. The ground tone need not necessarily be unalterable. Small steady variations at either the transmitter or receiver will not affect the operativeness 40 of the apparatus, but will only change the pitch of the ground tone on which the transitory signal variations of tone break in. Thus exact mutual adjustment of the two 45 frequencies is not required, and the receiving operator may adjust his own frequency

so as to produce the most efficient ground tone whose signal variations are easily read.

The oscillating circuit at the receiver may be and preferably is tuned to the transmitter frequency, to take advantage of the intensified currents due to resonance. The difference in the transmitter frequency for the signal and no-signal states may be so small that the receiving oscillating circuit when tuned to one frequency is practically in tune 60 with the other frequency. This difference is preferably so small as to be beyond the range of any tuning device not embodying the principle of differential frequencies. The signals are thus unobservable by any 65 other known form of receiver. With such receivers they will seem to be a continuous wave train of unvarying frequency and intensity.

70 With my present method the oscillator of my Patent No. 829,934 may be employed both at the transmitter and at the receiver. This oscillator generates undamped or sustained oscillations whose frequency depends upon the electrical constants of the system, and abrupt changes in this frequency can be readily made by altering such electrical constants.

75 It is convenient to use the same oscillator alternately for sending and receiving.

80 As a limiting case of this method, when the transmitter and receiver oscillations are normally (*i. e.*, in the no-signal state) exactly in tune the normal condition will be one of silence (no beats) broken by an 85 audible beat tone when the transmitter is thrown out of tune to produce signals. Conversely, if the frequency of the receiver oscillations be exactly the same as the frequency of the transmitter signal impulses, 90 the normal condition will be an audible beat tone broken by intervals of silence representing the signals. A similar result may be secured in a more practical way by using a mono-telephone, a vibration galvanometer 95 or relay, or other mechanically tuned receiving device, tuned to the beat frequency of the signal beats. This will then respond only to the signal tone, the ground note producing no effect. The signals will thus 100 stand out from a normal state of silence as when intermittent signals are employed. Or the receiver may be tuned to respond to the ground tone and to neglect the signal tone, the signal then being produced by 105 110

the intervals of silence. It is obvious that the beats need not be audible or even of an audible frequency, provided a receiver is employed capable of discriminating between 5 the beat frequencies corresponding to the signal and no-signal conditions, such as a vibration galvanometer or relay, in which case the signals may be visually displayed or be recorded or both. Thus are combined 10 the extreme selectivity arising from mechanical tuning to beats as described in my application referred to with the secrecy due to the minutely varying frequency of the continuous wave trains.

15 The variations of frequency at the transmitter may be readily produced by altering the electrical constants of the system in any of the ways described in my patent referred to, or in any other suitable way, such as by 20 relatively moving two portions of the oscillator inductance thereby changing their mutual induction and hence the effective inductance of the system, or by altering the distance between the plates of a condenser 25 thereby changing the effective capacity of the system.

A numerical example will illustrate the very small change of frequency required at the transmitter in operating in accordance 30 with my present method to produce readily distinguishable audible tones. Suppose the frequency of the sending oscillator be 100,000 cycles per second and that of the receiving oscillator be 99,500 cycles per second, or $\frac{1}{2}\%$ less. Then the beat frequency will be 100,000—99,500=500 beats (cycles) per second—a rather high pitched musical note. If now the sender frequency be changed to 100,050 cycles per second ($\frac{1}{2}\%$ higher) the 35 beat frequency will become 550 cycles per second—a change of 10%, or nearly a whole tone of the musical scale, a marked interval easily observed. If the sender frequency be 100,000 and the receiver frequency be 45 99,900 ($\frac{1}{10}\%$ below sender) the beat frequency will be 100 (cycles) per second (a fairly low note) and a difference of only 10 oscillations or 1 in 10,000 will produce a 10% change in the beat frequency. A minute change in the sender frequency will 50 therefore produce a relatively large change in the beat frequency.

In the accompanying drawing is illustrated one arrangement of apparatus by 55 means of which the method described can be carried out.

Figure 1 is a diagram representing the transmitter and Fig. 2 is a diagram representing the receiver. The transmitting oscillator A is illustrated as a simple form of the apparatus described in my Patent No. 829934 above referred to and consists of the vacuum tube 3 having two anodes 4 and a cathode 5. The anodes are connected in series in an oscillating circuit containing in-

ductances 6, 7 and capacity 8. The anodes are shunted by a circuit containing choke coils 9, 10, and between these choke coils a connection is made through the primary battery 11 to the cathode 5. The sending key 12 is shown as shunting a small portion of the inductance 6. The oscillating circuit including the oscillator is coupled with the antenna 13 by means of a transformer 14, the primary of which is formed by the inductance 7. At the receiving station the oscillator B, of the same character as the oscillator A already described, is connected in an oscillating circuit including inductances 15, 16, and capacity 17. This oscillating circuit is coupled by a transformer with a tuned oscillating circuit 18 containing inductances 19, 20 and also including the detector 21 which is illustrated as an electrostatic telephone. The transformer 22 coupling the two oscillating circuits has its primary formed by the inductance 15, and its secondary by the inductance 19. The tuned oscillating circuit 18 is coupled with the antenna 22 by means of a transformer 23 whose primary is formed by the inductance 20. Other arrangements of the transmitter apparatus may be employed and any of the forms of receiver described in my application referred to may be utilized in carrying out my present method.

What I claim is:

1. The method of transmitting and receiving sustained alternating signal impulses, which consists in transmitting a continuous wave train of sustained oscillations, changing the frequency of such continuous wave train to produce signals, combining with current oscillations produced by such transmitted wave train in a common element 100 of a tuned circuit at the receiver locally generated sustained current oscillations and observing the combined effects of such oscillations.

2. The method of transmitting and receiving sustained alternating signal impulses, which consists in transmitting a continuous wave train of sustained oscillations, changing the frequency of such continuous wave train to produce signals, combining 110 with current oscillations produced by such transmitted wave train in a common element of a tuned circuit at the receiver locally generated sustained current oscillations of a different frequency and observing the beats 118 produced by the combination of the effects of such oscillations.

3. The method of transmitting and receiving sustained alternating signal impulses, which consists in transmitting a continuous wave train of sustained oscillations, combining with current oscillations produced by such transmitted wave train in a common element of a tuned circuit at the receiver locally generated sustained current 125 oscillations.

oscillations of different frequency producing by this combination a definite beat rate, changing the frequency of the transmitted wave train to transmit signals producing at 5 the receiver a different beat rate, and observing either or both beat rates.

4. The method of transmitting and receiving sustained alternating signal impulses, which consists in transmitting a con-

tinuous wave train of sustained oscillations, combining with such transmitted wave train at the receiver locally generated sustained oscillations of different frequency producing by combination with the transmitted

wave train beats corresponding with an audible tone, abruptly changing the frequency of the transmitted wave train to transmit signals producing at the receiver beats corresponding with a different audible

20 tone, and observing either or both tones.

5. The method of transmitting and receiving sustained alternating signal impulses, which consists in transmitting a continuous wave train of sustained oscillations,

25 abruptly changing the frequency of said wave train to produce signals, combining with current oscillations produced by such transmitted wave train at the receiver locally generated sustained current oscillations and observing such combined oscillations by a receiver adapted to discriminate

30 between the beat rates resulting from the different frequencies.

6. The method of transmitting and receiving sustained alternating signal impulses, which consists in transmitting a continuous wave train of sustained oscillations, abruptly changing the frequency of said wave train to produce signals, combining

40 with such transmitted wave train at the receiver locally generated sustained oscillations and observing such combined oscillations by a receiver adapted to respond only to the beat rate produced by the signal frequency.

7. The method of transmitting and receiving sustained alternating signal impulses, which consists in transmitting a continuous wave train of sustained oscillations,

50 producing signals by abrupt changes in the frequency of such wave train too small to

be effectively observed by electrical resonance and observing the minute variations in frequency of such transmitted wave train by comparison with a locally generated oscillation of definite frequency. 55

8. The method of transmitting and receiving sustained alternating signal impulses, which consists in transmitting a continuous wave train of sustained oscillations, abruptly changing the frequency of such continuous wave train to produce signals, combining with such transmitted wave train at the receiver locally generated sustained oscillations and observing the combined effects of such oscillations. 60

9. The method of transmitting and receiving sustained alternating signal impulses, which consists in generating sustained electrical oscillations, whose frequency depends upon the electrical constants of the system, producing and transmitting by such oscillations a continuous wave train, altering the electrical constants of the system to produce signals by changes in the frequency of such wave train too small to be effectively observed by electrical resonance and observing the minute variations in frequency of such transmitted wave train by comparison with a locally generated oscillation of definite frequency. 70

10. The method of transmitting and receiving sustained alternating signal impulses, which consists in generating sus-

tained electrical oscillations, whose frequency depends upon the electrical constants of the system, producing and transmitting by such oscillations a continuous wave train, altering the electrical constants of the system to produce signals by changes in the frequency of such wave train, combining with such transmitted wave train at the receiver locally generated sustained oscillations and observing the combined effects of such oscillations. 80
